UNITED STATES PATENT OFFICE

2,393,912

COUPLER

Frank H. Kayler, Alliance, Ohio, assignor to
 American Steel Foundries, Chicago, Ill., a corporation of New Jersey

Application September 18, 1943, Serial No. 502,872

26 Claims. (Cl. 213—148)

My invention relates to a railway car coupler and more particularly to an improved form of rotor operating mechanism and anticreep.

The general object of my invention is to devise a rotary mechanism having a more positive anticreep than any heretofore applied.

Another object of my invention is to devise a rotary mechanism and anticreep which will be interchangeable with the present Standard E mechanism as now used throughout the United States.

In the present Standard E coupler the rotary mechanism utilizes a so-called toggle which is connected to the bottom leg of the lock, a rotor which at one end is connected to the toggle and at the other end is mounted for rotary motion on a lug at the rear end of the coupler, said rotor having an opening therethrough intermediate its ends for connection to the eye end of an associated operating rod. Under certain operating conditions, it has been found that the anticreep arrangement of the present standard type E coupler is not altogether positive to prevent accidental unlocking of the coupler and under such conditions, train partings have resulted. It is fairly well understood that the unusual combination of conditions which occasionally causes such accidents results when vertical bouncing of the cars is combined with a run-together or run-in of slack, which may be occasioned, for example, by an abrupt stop or sudden reduction of speed.

Quick vertical movement of the coupler may be caused not only by bouncing of the cars but by a sharp buffering action which may occur during the run-in of slack, and this is particularly the case with respect to coupler heads which, because of various conditions of wear, may have dropped somewhat below the normal position. The sudden buffering action may bring the couplers up to normal level with a sharp movement which may be suddenly stopped as pressure is brought to bear between the buffering faces of mating couplers. At such an instant the lock may continue its upward movement, if not prevented by an effective anticreep.

In the rotary operating arrangement of the present Standard E coupler, the inner end of the operating rod being supported as above-mentioned in an eye of the rotor at a level substantially below the support of the lever itself, any operating condition tending to cause the inner end of the rod to move forward, such as momentum of the rod during a run-in of slack, a rotary motion of the rotor lever will be caused by such forward movement of the rod. Rotary

movement of the rotor will release the anticreep, and if this occurs at the same instant as happens such a vertical movement as above-indicated when there is no tension on the knuckle, the lock may be thrown upward at the instant the anticreep is free. In such a case, if the upward thrust is sufficiently severe, the lock may be raised entirely above the knuckle, thus unlocking it and causing a train parting.

My novel device is designed to prevent unlocking of the lock under such conditions as those described and consists, generally speaking, of the provision of the substitution of a two-piece rotor, hinged with respect to each other, which is interchangeable with the present one-piece rotor and certain other details of modification as may be hereinafter described.

In the drawings,

Figure 1 is a fragmentary sectional view in a longitudinal plane through the rear portion of a Standard E coupler, the section being taken in a plane substantially bisecting the trunnion bar on the coupler head which affords support for the rotor and wherein my novel form of rotor and anticreep arrangement is illustrated with the parts thereof shown in elevation and in normal locked position.

Figure 2 is a view comparable to Figure 1, illustrating the position of the parts when the end of the operating rod is thrown forward.

Figure 3 is a further view comparable to Figures 1 and 2, illustrating the character of the auxiliary anticreep afforded by my novel mechanism under certain operating conditions.

Figure 4 illustrates the position of the parts when the operating rod is rotated to release the anticreep in a normal unlocking operation.

Figure 5 is a top plan view of the rotor lever assembly, and Figure 6 is a rear view thereof or a view taken from the right as seen in Figure 5.

In the view of Figure 1, my novel arrangement is shown as applied to a Standard E coupler with the parts in normal locked position. As there illustrated, a fragmentary portion is shown of the coupler head 2 including the bottom portion of the lock cavity 4 in which may be seen the bottom leg 6 of the lock and at the rear of the coupler head may be noted the lug 8, affording support for the trunnion 10 on which may be carried the hook end 12 of the coupler engaging or rear portion, generally designated 14, of my novel two-piece form of rotor. The said rear portion 14 may be pivotally connected or hinged as at 16 by the rivet 18 to the forward portion 55 of said rotor, said forward portion being gen-

erally designated 20 and including an intermediate opening or eye 22 (Figure 5) in which may be received the looped end 24 of the standard operating rod. The forward end of the rotor piece 20 may have pivotal connection as at 26 to the link or toggle 28, said toggle having the form at present standard in the type E coupler. The upper end of said toggle may have a horizontal trunnion portion 30 received in the slot 32, formed for that purpose at the lower end of the lock leg 6. With the parts as thus illustrated in normal locked position, the anticreep ledge or lug 34, adjacent the upper end of the toggle 28, underlies the anticreep lug 36 on the forward wall of the lock cavity 4.

The rear member 14 of my articulated rotor incorporates the middle hub 38 of the hinge connection to the associated member, said hub 38 fitting between the spaced walls 40, 42 (Figure 6) formed at the rear extremity of the associated member 20 and joined by the tie bar 43 extending therebetween. With the parts in normal position as thus described, the pivot points 16 and 26 lie substantially vertically beneath the respective suspension points afforded the rotor mechanism in the hub 10 and the trunnion 36. When in this position, there is a space indicated at 44 between the ledge 46 of the member 20 and the adjacent flat wall 48 on the forward side of the member 14, said space indicating that the parts normally hang in what may be described as a slightly opened position of the hinged connection.

Referring now to Figure 2, there is illustrated the condition which exists when the eye end of the operating rod and the rotor mechanism is thrown forward as a result of such a combination of forces as heretofore referred to. When the device is thus thrown in a forward direction, the end of the operating rod 24 is somewhat elevated owing to the swinging action of the rotor and toggle, the normal position of the rod 24 in relation to said elevated position being illustrated in phantom lines at 50. With my novel arrangement when the parts have swung forward as illustrated in Figure 2, the auxiliary anticreep lug 52 abuts as at 54 the under side of the coupler wall 56, preventing further upward movement of the toggle 28 and the associated lock leg 6. As illustrated in Figure 2, the lock is shown raised the maximum possible amount for this position of the parts. It will be understood, of course, that under varying operating conditions, the swing of the rotor parts might proceed even further in a forward direction until the toggle 28 might engage at 58 the adjacent side of the wall 56, or, if the parts were swung forward a lesser amount, the auxiliary anticreep 52 would have a minimum engagement at the bottom face of the wall 56, as illustrated at 60 in Figure 3. In either of these positions, however, as shown in Figures 2 and 3, the present standard anticreep lug 34 is still positioned beneath the cooperating ledge or lug 36 in the front wall of the lock cavity. In both of these figures the lock is illustrated at its maximum elevation under the conditions shown and its relative position is indicated by the normal locked position shown in phantom lines at 61. It will be seen, therefore, that in case the parts, for example, assume the position illustrated in Figure 2 and then move rearwardly to the position illustrated in Figure 3, or even further, the normal anticreep lugs 34, 36 will be in operative position.

By my novel arrangement, excessive swing of

the operating rod handle is prevented. This results from the fact that when the auxiliary anticreep 52 strikes the bottom face of the coupler wall 56, rotation of the operating rod 24 is limited by the fact that the eye end thereof seats at one side as at 62 (Figure 2) in the eye 22 and seats at the opposite side thereof as at 64, the amount of such movement to and fro being indicated by the angle included at 66.

By my novel arrangement, the combination of an auxiliary anticreep with the regular standard anticreep acts positively to prevent accidental unlocking under the various possible combinations or sequences of vertical and horizontal forces which might otherwise cause accidental unlocking of the coupler when fitted with parts at present accepted as standard. In my novel arrangement the weight of the operating rod, which is supported in the rotor below its trunnion connection to the coupler head, is advantageous in that movement of the operating rod is effective to bring the articulated rotor lever arrangement into position where the auxiliary anticreep may become effective; whereas, under present standard conditions, such movement of the operating rod is objectionable because it acts to turn the rotor about its pivotal connection with the trunnion 10, thus tending to release the anticreep by movement of the parts to the relative positions illustrated in Figure 4.

Figure 4 shows the position taken by the parts during manual operation of unlocking the coupler by means of the operating rod. Such rotation of the rod brings the eye thereof into engagement with the part 20 as at 62 and 64 so that the two parts of the articulated rotor are closed with respect to each other, the lug 46 abutting the wall 48 as at 70, and further engagement between the articulated members being afforded as at 72 at the opposite side of the pivot point 16 where the before-mentioned tie bar 43 may afford an abutment for the extremity 45 of the hub 38. Under these conditions, the two articulated portions 14 and 20 are rigid with respect to each other and operate the same as the present standard one-piece rotor, and the length of my novel articulated lever when so closed is the same from pivot point 16 to pivot point 26 as the present standard one-piece rotor.

Thus, normal manual actuation of the operating rod 24 moves the articulated portions of my novel rotor into closed engagement with each other so that the two operate substantially identically for that purpose, as does the present Standard E rotor. When so actuated, the auxiliary anticreep lug 52 will swing around with plenty of clearance from the adjacent bottom edge 74 of the wall 56 and move upwardly into the lock cavity as the lock itself is elevated by engagement as at 76 of the link trunnion 30 at the top of the slot 32 in the leg of the lock. Under these conditions, of course, the normal anticreep 34, 36 is free of engagement, as also is the auxiliary anticreep afforded at 52.

The rotary force manually applied to the operating rod keeps the articulated rotor in closed position as the lock is unlocked and the knuckle thrown. When this force is released, the weight of the rod and associated parts keeps the articulated rotor in the closed position until the parts swing back to the normal position illustrated in Figure 1 when the articulated connection may open slightly as there illustrated.

It will thus be seen that my novel arrangement of an articulated two-piece rotor as herein

described is effective when associated with present Standard E coupler parts to provide an auxiliary anticreep and to increase the effectiveness of the anticreep means at present utilized therein.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. A coupler having a lock and an adjacent support, operating means for said lock having one end hung from said support and the other end from said lock, said operating means comprising a toggle connected to said lock, a two-piece articulated rotor pivotally connected at respective ends to said toggle and said support, the respective pieces of said rotor having engageable stop means at opposite sides of their pivotal connection, said stop means limiting the relative rotation of said pieces in a direction to unlock said lock, operating means connected to one of said pieces, and anticreep means on one of said pieces operative to engage said coupler and prevent unlocking of said lock when said pieces are relatively rotated in the opposite direction, relative rotation of said pieces in said opposite direction to the point where said anticreep is engaged being effective to restrict the rotational movement of said operating means, and means on one of said pieces engageable with said operating means to restrict accidental swinging movement thereof upon engagement of said anticreep means with said coupler.

2. In a coupler structure, a coupler head having front and rear walls defining in part a lock cavity, a trunnion on said rear wall, a lock in said cavity, a link hung from said lock, an articulated rotor hung from said trunnion and pivotally connected to said link, said link and rotor being capable of swinging movement from the respective points of support on said lock and said trunnion wherein relative movement occurs between the articulated portions of said rotor, means on one of said portions normally underlying said front wall to afford an anticreep, and an operating rod connected to one of said portions, movement of said operating rod in a direction to unlock said coupler causing limited relative movement between said articulated portions to a position where they become fixed with respect to each other and operate as a single member during such further movement, rotation of said portions to said relatively fixed position being effective to release said anticreep.

3. A two-piece articulated rotor for a coupler operating means, means at opposite ends of said rotor having pivotal connection to associated support means, an opening in one of said pieces for connection to an associated operating rod, and stop means on said pieces at opposite sides of their articulated connection limiting relative rotation therebetween in an unlocking direction, further rotation thereof in said direction causing said pieces to operate as a rigid one-piece structure wherein the distance between the pivotal points of support thereof is equal to the distance between the pivotal points of support of the present Standard E coupler rotor, relative rotation of said pieces in an unlocking direction being effective to increase the distance between said pivotal points of support at opposite ends thereof

and thus to bring an anticreep on one of said pieces into position to engage a portion of the associated coupler.

4. In a coupler structure, a coupler head having front and rear walls defining in part a lock cavity, a trunnion on said rear wall, a lock in said cavity, a link hung from said lock, an articulated rotor hung from said trunnion and pivotally connected to said link, said link and rotor being capable of swinging movement from the respective points of support on said lock and said trunnion wherein relative movement occurs between the articulated portions of said rotor, whereby means on one of said portions underlies said front wall to afford an anticreep, and an operating rod connected to one of said portions, movement of said operating rod in a direction to unlock said coupler causing limited relative movement between said articulated portions to a position where they become fixed with respect to each other and operate as a single member during such further movement.

5. In a coupler arrangement, a coupler head having forward and rear walls defining in part a lock cavity, a trunnion on said rear wall, a lock in said cavity, a link hung from said lock, opposed anticreep lugs on said forward wall and said link, an articulated rotor supported adjacent respective ends from said trunnion and said link, and operating means connected to said rotor, said rotor comprising forward and rear portions pivoted to each other at a point normally positioned substantially vertically beneath said trunnion when said coupler and the associated parts are at rest in normal locked position, and the pivotal connection between said link and said rotor being substantially vertically below the point of support of said link on said lock when said parts are so positioned.

6. A coupler having a lock and an adjacent support, operating means for said lock having one end hung from said support and the other end from said lock, said operating means comprising a toggle connected to said lock, a two-piece articulated rotor pivotally connected at respective ends to said toggle and said support, the respective pieces of said rotor having engageable stop means at opposite sides of their pivotal connection, said stop means limiting the relative rotation of said pieces in a direction to unlock said lock, operating means connected to one of said pieces, and anticreep means on one of said pieces operative to engage said coupler and prevent unlocking of said lock when said pieces are relatively rotated in the opposite direction.

7. A coupler having a lock, a link hung from said lock and a two-piece articulated rotor pivotally connected to said link and to support means on said coupler, and an operating rod connected to one of said pieces, accidental swinging movement of said rotor being effective to cause articulation between said pieces and increase the distance between the pivot points at its opposite ends, thus bringing an anticreep member on one of said pieces in a position to underlie a portion of said coupler, and manual operation of said rod being effective to cause relative rotation of said pieces in the reverse direction to engage opposed stop means thereon and reduce said distance, thus freeing said anticreep for unlocking said lock.

8. A two-piece articulated rotor for coupler operating means, means at opposite ends of said rotor having pivotal connection to associated support means, an opening in one of said pieces

for connection to an associated operating rod, and stop means on said pieces at opposite sides of their articulated connection limiting relative rotation therebetween in an unlocking direction, further rotation thereof in said direction causing said pieces to operate as a rigid one-piece structure wherein the distance between the pivotal points of support thereof is equal to the distance between the pivotal points of support of the present Standard E coupler rotor.

9. In a coupler arrangement, a coupler head having forward and rear walls defining in part a lock cavity, a trunnion on said rear wall, a lock in said cavity, a link hung from said lock, opposed anticreep lugs on said forward wall and said link, an articulated rotor supported adjacent respective ends from said trunnion and said link, and operating means connected to said rotor, said rotor comprising forward and rear portions pivoted to each other at a point normally positioned substantially vertically beneath said trunnion when said coupler and the associated parts are at rest in normal locked position.

10. In a coupler structure, a coupler head having front and rear walls defining in part a lock cavity, a trunnion on said rear wall, a lock in said cavity, a link hung from said lock, and an articulated rotor hung from said trunnion and pivotally connected to said link, said link and rotor being capable of swinging movement from the respective points of support on said lock and said trunnion wherein relative movement occurs between the articulated portions of said rotor, whereby means on one of said portions underlies said front wall to afford an anticreep.

11. In a coupler structure, a coupler head having front and rear walls defining in part a lock cavity, a trunnion on said rear wall, a lock in said cavity, a link hung from said lock, an articulated rotor hung from said trunnion and pivotally connected to said link, said link and rotor being capable of swinging movement from the respective points of support on said lock and said trunnion wherein relative movement occurs between the articulated portions of said rotor, whereby means on one of said portions underlies said front wall to afford an anticreep, and an operating rod connected to one of said portions.

12. A coupler having a lock and an adjacent support, operating means for said lock having one end hung from said support and the other end from said lock, said operating means comprising a toggle connected to said lock, a two-piece articulated rotor pivotally connected at respective ends to said toggle and said support, the respective pieces of said rotor having engageable stop means at opposite sides of their pivotal connection, said stop means limiting the relative rotation of said pieces in a direction to unlock said lock, and operating means connected to one of said pieces.

13. In a railway car coupler, a coupler head having a lock cavity and an integral trunnion at the rear thereof, a lock supported in said cavity, a toggle link connected thereto at its upper end, an articulated two-piece rotor pivotally connected at its forward end to said toggle and having its opposite end supported on said trunnion, and an opening in said rotor for connection of an associated operating rod, said articulated rotor comprising forward and rear portions hinged to each other and capable of limited relative movement with respect to each other.

14. A coupler having a lock and an adjacent

support, operating means for said lock having one end hung from said support and the other end from said lock, said operating means comprising a toggle connected to said lock, and a two-piece articulated rotor pivotally connected at respective ends to said toggle and said support, the respective pieces of said rotor having engageable stop means at opposite sides of their pivotal connection, said stop means limiting the relative rotation of said pieces in a direction to unlock said lock.

15. A two-piece articulated rotor for coupler operating means, means at opposite ends of said rotor having pivotal connection to associated support means, an opening in one of said pieces for connection to an associated operating rod, and stop means on said pieces at opposite sides of their articulated connection limiting relative rotation therebetween in an unlocking direction, further rotation thereof in said direction causing said pieces to operate as a rigid one-piece structure.

16. A coupler having a lock, a link hung from said lock and a two-piece articulated rotor pivotally connected to said link and to support means on said coupler, and an operating rod connected to one of said pieces, accidental swinging movement of said rotor being effective to cause articulation between said pieces and increase the distance between the pivot points adjacent its opposite ends, thus bringing an anticreep member on one of said pieces in a position to underlie a portion of said coupler.

17. In a railway car coupler, a coupler head having a lock cavity and an integral trunnion at the rear thereof, a lock supported in said cavity, a toggle link connected at its upper end to said lock, an articulated two-piece rotor having its forward piece connected to said toggle link and having its opposite piece supported on said trunnion, and an opening in said forward piece for connection of an associated operating rod.

18. In a coupler arrangement, a coupler head having forward and rear walls defining in part a lock cavity, a trunnion on said rear wall, a lock in said cavity, a link hung from said lock, opposed anticreep lugs on said forward wall and said link, an articulated multi-piece rotor supported adjacent respective ends from said trunnion and said link, anticreep means on the forward piece of said rotor, and operating means connected to said rotor, the normal weight of said operating means being operable to urge said rotor to its open position wherein said anticreep means underlies a portion of said forward wall.

19. In a coupler arrangement, a coupler head having forward and rear walls defining in part a lock cavity, a trunnion on said rear wall, a lock in said cavity, a link hung from said lock, opposed anticreep lugs on said forward wall and said link, an articulated multi-piece rotor supported adjacent respective ends from said trunnion and said link, the forward piece of said rotor having means for connection to associated operating means.

20. In coupler operating means, a two-piece articulated rotor, each of said pieces having stop means at opposite sides of their pivot connection limiting their relative rotation in one direction, an opening through the forward of said pieces for connection to an associated operating rod, said forward piece having an anticreep lug forwardly of said opening and formed and arranged

for engagement with anticreep means of an associated coupler.

21. In coupler operating means, a multi-piece articulated rotor, the respective pieces thereof having means limiting relative rotation therebetween in one direction, the forward of said pieces having connecting means for engagement with an associated operating element, and the rearward of said pieces having pivot means for connection to an associated coupler, and anticreep means on said forward piece adapted for engagement with anticreep means of said coupler.

22. In coupler operating means, a multi-piece articulated rotor, the respective pieces thereof having means limiting relative rotation therebetween in one direction, an opening through the forward of said pieces for connection to an associated operating rod, and the rearward of said pieces having means for pivotal connection to an associated coupler, and anticreep means on said forward piece forwardly of said opening and adapted for engagement with anticreep means on said coupler.

23. A multi-piece coupler operating rotor comprising a plurality of pivotally interconnected members, connecting means on one of said members for associated actuating means, and anticreep means on said rotor formed and arranged for engagement with anticreep means of an associated coupler.

24. A multi-piece coupler operating rotor comprising a plurality of pivotally interconnected members, connecting means on one of said members for associated actuating means, and anti-

creep means on said rotor forwardly of said connecting means adapted for engagement with anticreep means of an associated coupler, the rearward of said members having means for pivotal connection to said coupler.

25. A coupler having a lock, a two-piece articulated rotor having a pivotal connection at one end thereof to said coupler and an operative connection at the opposite end thereof to said lock, operating means connected to one of said pieces, said pieces being capable of relative pivotal movement during accidental swinging of said rotor whereby the distance between the ends of said rotor is increased, and anticreep means on one of said pieces for engaging anticreep means on said coupler during said pivotal movement.

26. A coupler having a lock, a multi-piece articulated rotor having a pivotal connection at one end thereof to said coupler and an operative connection at the opposite end thereof to said lock, operating means operatively connected to one of said pieces, means accommodating relative pivotal movement between the pieces of said rotor during accidental swinging movement thereof, whereby the distance between the ends of said rotor is increased during said swinging movement, and anticreep means on one of said pieces for engaging anticreep means on said coupler during said swinging movement, whereby accidental upward movement of said rotor during said swinging movement thereof is positively limited.

FRANK H. KAYLER.
